UNITED STATES PATENT OFFICE.

HUGO TUECKMANTEL, OF IRVINGTON, NEW JERSEY, ASSIGNOR TO THE R. NEUMANN HARDWARE CO., A CORPORATION OF NEW JERSEY.

BAG-FRAME FASTENER.

1,104,455.

Specification of Letters Patent. Patented July 21, 1914.

Application filed November 25, 1913. Serial No. 802,873.

To all whom it may concern:

Be it known that I, HUGO TUECKMANTEL, a citizen of the United States, residing at Irvington, in the county of Essex and State 5 of New Jersey, have invented certain new and useful Improvements in Bag-Frame Fasteners; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification. 15

The present invention has reference, generally, to improvements in that class of fastening or locking devices, known in the art 20 as bag-frame fasteners; and, the invention relates more particularly, to an improvement in the form of bag-frame fasteners set forth in my former Letters-Patent No. 1,032,814, and dated July 9th, 1913, with a 25 view of dispensing with the usual hollow or chambered finger-piece, slidably disposed upon the upper surface of the main chambered body or shell of the bag-frame fastener, and substituting therefor a slidable finger-piece in the form of a flat plate.

The invention, therefore, has for its principal object to provide a neat and simply 30 constructed bag-frame fastener of the general construction hereinafter set forth, and the slidable finger-piece of which is made in 35 the form of a flat-plate, whereby the outward appearance of the device is generally enhanced.

The invention has for its further object to 40 provide the main chambered body or shell of the bag-frame fastener with a thumb-receiving depression, normally located beneath the one end-portion of the flat or plate-like finger-piece, which enables the operator to 45 more easily manipulate the fingerpiece, as will hereinafter more fully appear.

Other objects of the invention not at this 50 time more particularly enumerated will be clearly understood from the following detailed description of the present invention.

With the various objects of the present invention in view, the invention consists, primarily, in the novel bag-frame fastener hereinafter set forth; and, the invention consists, furthermore in the novel arrangements and

combinations of the various parts of the 55 same, as well as in the details of the construction of the said parts, all of which will be more fully described in the following specification, and then finally embodied in the clauses of the claim which are appended 60 to and which form an essential part of this specification.

The invention is clearly illustrated in the accompanying drawings, in which:—

Figure 1 is a front-side elevation of a 65 bag-frame fastener or catch, shown attached to a portion of the frame-section comprising a bag-frame, and embodying the principles of the present invention; and Fig. 2 is a top or plan view of the bag-frame fastener in its attached relation upon one of the frame-sections, the finger-piece and main body of the fastener being represented in their normal relations, one to the other, and said view being made on an enlarged scale. 70 Fig. 3 is a longitudinal vertical section of the bag-frame fastener or catch removed from its relation with the bag-frame, said view being made on a still larger scale; and Fig. 4 is a view, similar to that represented 75 in said Fig. 2, and made on the same scale, illustrating the position of the flat or plate-like finger-piece to the main body of the fastener, when the finger-piece has been operated. Fig. 5 is an end view of the bag- 80 frame fastener or catch; and Fig. 6 is a top or plan view of the main body-portion of the fastener, the finger-piece having been 85 omitted from said view.

Similar characters of reference are em- 90 ployed in the said above described views, to indicate corresponding parts.

Referring now to the several figures of the drawings, the reference-character 1 indicates the main chambered body or base 95 of the bag-frame fastener, the same being preferably of elongated and rectangular configuration, which is surrounded by a flange 2 and from which extend at suitable intervals, and usually at the ends of the said 100 main body or base, suitable fastening lugs or prongs 3 which are adapted to be inserted in correspondingly placed holes or slots, in one of the said bag-frame sections, as 4, and are bent over upon the under surface of said 105 frame-section, as will be clearly understood from an inspection of and as is represented in Fig. 1 of the drawings. In its flat face-

portion 5, the said chambered body or base is provided with a longitudinally extending slot or opening, as 6, and a transversely extending slot, as 7, as shown in Fig. 6 of the drawings, and for the purposes stated in my said former Letters Patent No. 1,032,314 herein - above mentioned. Mounted upon the said flat upper face-portion 5 of the chambered body or base 1 is a flat plate, as 8, of the general configuration shown in the several figures of the drawings, the said flat plate being adapted to slide longitudinally upon the said upper face-portion 5, and its marginal outline corresponding to the marginal outline of the face-portion of the main body or base of the bag-frame fastener, so that the said parts of the device, when in their normal locking relation, will be fitted upon each other and will have the appearance of one complete shell or casing. Suitably secured to the under face of the said flat-plate 8, by means of suitable fastening lugs, as 10, which extend into suitably disposed holes 11 in said plate 8, and riveted fast to said plate in any suitable manner, is a downwardly extending locking post 9, the said locking post thus being rigidly connected with the slide or finger-piece formed by said flat plate 8, and the said locking post projecting into and through, and being movably disposed in the previously-mentioned longitudinal slot or opening 6 in the upper flat portion 5 of the chambered main body or base of the device. The outer end-portions of the said locking post 9 are also provided with suitably formed projections or lugs, as 12 which extend through the slotted portion 14 of a flat spring 13 and are bent over upon the back of said spring, in the manner of my said former Patent No. 1,032,314, and as illustrated in Fig. 3 of the drawings, for holding all of the parts in their operative and assembled relation. The said flat spring 13 is also made with a transversely and upwardly projecting rib-like portion, as 15, and made in the manner set forth in my said former Patent No. 1,032,314, and which, under normal conditions, rests in the transversely extending slot 7 so as to hold the slide or finger-piece in its normal position when not in operation, and to help bring it back again to its normal position with surety and a snap, thus insuring to the operator the locked condition of the parts of the device.

Of course it will be evident, that the slide or fingerpiece 8, being made in the form of a flat plate of approximately thin metal, in operating the slide in the direction of the arrow α , see Fig. 3, there might be a possibility of the thumb or finger of the operator sliding off the thin narrow edge-portion 16 of the plate 8, and to avoid this, the upper flat surface-portion 5 of the main chambered

body or base 1 of the body of the fastener is provided at one end, and directly beneath the said edge-portion 16 of the slide or fingerpiece 8 with a downwardly depressed part, as 17, which tapers in an upward direction toward the middle of the upper flat face-portion 5 of the said body and thereby provides a suitable thumb or finger-receiving depression 18, for the reception of that part of the thumb or finger which projects beneath the edge of the plate 8 when manipulating the same. 70

While I have in the present application illustrated the use of a flat plate-like slide or fingerpiece and a chambered main body provided with a thumb or finger-receiving depression, in connection with the construction of bag-frame fastener represented in my said former Letters Patent No. 1,032,314, I am fully aware that the features embodying the principles of the present invention may likewise be applied to other constructions of bag-frame fasteners entailing the use of a main chambered body or base and a flat plate-like slide or fingerpiece movably disposed upon said chambered body or base. It will be obvious, therefore, that changes may be made in the general arrangements and combinations of the various parts without departing from the scope of the present invention as set forth in the foregoing specification, and as defined in the clauses of the claims which are appended to the said specification. Hence, I do not limit my present invention to the exact arrangements and combinations of the various devices and parts as described in the foregoing specification, nor do I confine myself to the exact details of the construction of the said parts, as illustrated in the accompanying drawings. 80 85 90 95 100 105

I claim:

1. A bag-frame fastener for bag frames and the like, comprising a main chambered body or base, said body being provided with an upper flat surface formed at one end with a thumb or finger-receiving depression, and a flat plate-like member movably disposed upon said upper flat surface of said body or base and normally extending over

said receiving depression, for the insertion of the finger beneath said plate-like member, for the manipulation of the same and of the locking mechanism of the bag-frame fastener. 110 115 120

2. A bag-frame fastener for bag frames and the like, comprising a main chambered body or base, said body being provided with an upper flat surface formed at one end with a thumb or finger-receiving depression, the upper flat surface of the said main body or base being also provided with a longitudinally extending slot, a flat plate-like member movably disposed upon said upper flat surface of said body or base and normally extending over said receiving depression, 125 130 135

for the extension of the finger beneath said plate-like member for the manipulation of the same, and a spring-controlled locking post extending downwardly from the said 5 plate-like slide and through the slot in said main body or base.

In testimony, that I claim the invention

set forth above I have hereunto set my hand this 24th day of November, 1913.

HUGO TUECKMANTEL.
